UNITED STATES PATENT OFFICE.

CHARLES S. DUVAL, OF HOLYOKE, MASSACHUSETTS.

DESIGN FOR A TAPPING-HAMMER.

45,907.

Specification for Design.

Patented June 9, 1914.

Application filed March 19, 1913. Serial No. 755,553. Term of patent 7 years.

To all whom it may concern:

Be it known that I, CHARLES S. DUVAL, a citizen of the United States of America, residing at Holyoke, in the county of Hampden and State of Massachusetts, have invented a new, original, and ornamental Design for Tapping-Hammers, of which the following is a specification, reference being had to the accompanying drawings, forming part thereof.

In the drawings, Figure 1 is a perspective

view of a tapping hammer, showing my new design, and Fig. 2 is a rear elevation of the same.

I claim:

The ornamental design for a tapping hammer as shown.

CHARLES S. DUVAL.
